CLAIM

The ornamental design for a fairway distance marker, as shown and described.

DESCRIPTION

FIG. 1 is a perspective view of the fairway distance marker showing a portion of my new design;
FIG. 2 is a front elevational view thereof, whereby the back elevational view is a mirror image thereof;
FIG. 3 is a side elevational view thereof, whereby the opposing side is a mirror image thereof;
FIG. 4 is a top plan view thereof; and,
FIG. 5 is a bottom plan view thereof.

FIG. 1

FIG. 2

FIG. 3

FIG. 4

FIG. 5
